Term of patent 14 years

(Cl. D48—32)

FIG. 4

Figure 1 is a front elevational view of a combined lamp lens and frame therefor, showing my new design;

Figure 2 is a front elevational view showing two of the devices to a smaller scale positioned as in use, the dotted lines indicating an automobile being for illustrative purposes only;

Figure 3 is a side elevational view;

Figure 4 is a top plan view;

Figure 5 is a fragmentary cross sectional view taken on the line 5—5 of Figure 1;

Figure 6 is a cross sectional view taken on the line 6—6 of Figure 1; and

Figure 7 is a fragmentary cross sectional view taken on the line 7—7 of Figure 1.

The characteristic features of my design reside in the portions shown by means of the full lines in the drawing.

I claim:

The ornamental design for a combined lamp lens and frame therefor, as shown and described.
